UNITED STATES PATENT OFFICE.

BERTRAM J. GOLDSMITH, OF NEW YORK, AND EMIL KOEB, OF TUCKAHOE, NEW YORK,
ASSIGNORS, BY MESNE ASSIGNMENTS, TO PERFECT WINDOW REGULATOR COR-
PORATION, OF LONG ISLAND CITY, NEW YORK, A CORPORATION OF DELAWARE.

WINDOW REGULATOR.

Application filed February 27, 1925. Serial No. 11,921.

This invention relates to mechanisms for raising and lowering windows and it is particularly adapted in its application to windows which are slidable in guideways in a 5 suitable frame such as in the doors of closed automobiles or other vehicles.

The principal object of the invention is the production of a window regulator of few parts, of simple construction and which 10 may be manually operated with little effort.

Other and further objects and advantages of the invention will appear from the accompanying description, the invention consisting in a novel window regulator herein- 15 after more particularly described and then specified in the claims.

The accompanying drawing illustrates a practical embodiment of the invention in which:

20 Fig. 1 is a front elevation of a fragmentary portion of a vehicle door showing the invention applied thereto.

Fig. 2 is a horizontal section on the line 2—2 of Fig. 1.

25 Referring in detail to both figures of the drawing:

1 indicates the side members of a rectangular frame of a door which are provided with suitable guideways or channels 2 therein receiving a slidable window pane 3 slidable into the usual window well one wall of which is indicated at 4 and the other wall of which is indicated at 5. 6 indicates a window sill or ledge extending across the side members 30 and fastened thereto in any desirable manner.

Mounted on one of the side members 1, by suitable screws as shown or otherwise, is a bracket 7 provided with extensions 8 and 40 9.

Pivoted to the extension 9 is a curved arm 10 having thereon a roller 11 adapted to ride in a channel 12 which is secured in any manner to the lower edge of the window 3.

45 The outer end of the flexible operating rod 10 is pivoted to a curved arm 12' extending upwardly adjacent the righthand side member 1 and supported by a perforated bracket 13 which is secured to the righthand side member 1 by suitable screws as shown. The operating rod 12' also extends through a suitable opening in the window sill 6 and it has secured thereto above the window sill an operating handle 14. The window is thus retained in any set position

by reason of the operating rod 12' binding 55 to some extent in the bracket 13. The free or movable end of the arm 10 is normally out of alignment with the opening through the bracket 13 thereby insuring a binding action between the rod 12' and bracket 13. 60 It is obvious that the bracket 13 and rod 12' may be provided with a supplemental locking or friction device if desired.

As will be obvious, pulling up or pressing down of the operating handle 14 operates 65 to raise or lower the window 3 in the guideways 2 as the roller rides in the channel 12 and very little effort is necessary for the raising or lowering operation due to the disposition of the various parts described 70 and the leverage attained on the handle. To assist in the raising of the window we attach one end of a counterbalance spring 15 to the extension 8 while the other end is attached to a suitable hook on the arm 10. 75 The parts all being carried or supported by the bracket 7, with the exception of the bracket 13, makes the shipping and installation of the device very simple.

What we claim as our invention is: 80

1. In a window regulator, a bracket, an arm pivoted at one end to said bracket, a spring connecting said arm and said bracket, window engaging means carried by said arm between the ends thereof, an operating rod pivoted to said arm adjacent the free or movable end thereof and means for securing said rod against movement. 85

2. In combination with a movable window, a curved, pivotally mounted arm, 90 means operatively connecting said arm and window at a point adjacent the topmost portion of said curve when said window is in raised position, an operating rod secured to said arm at a point outwardly of the 95 point of connection thereof with said window, and means for controlling said rod.

3. In a window regulator, a frame provided with a walled space therein, a window slidable in said frame and into said 100 walled space, a curved arm pivotally secured to said frame and provided with a window operating element adjacent the topmost portion of said curve when said window is in closed position, means for connecting said 105 element with said window, said arm being provided with an extension extending beyond said element, and a shiftable control

rod secured to said extension for moving said window.

4. In a window regulator, a frame provided with a walled space therein, a window 5 slideable in said frame and into said walled space, a curved arm pivotally secured to said frame and provided with a window operating element adjacent the topmost portion of said curve when said window is in closed 10 position, means for connecting said element with said window, said arm being provided with an extension extending beyond said element, a shiftable control rod secured to said extension for moving said window and a 15 counterbalancing spring attached to said arm adjacent the curve therein and secured to said frame above the pivotal point of connection of said arm and frame.

5. In combination with a movable window, 20 a pivoted arm, means operatively connecting said arm and window, a flexible operating rod pivotally connected to said arm at a point remote from the pivot thereof

and means for retaining said rod in set position.

6. In combination with a movable window, a pivoted arm, means operatively connecting said arm and window, a flexible operating rod pivotally connected to said arm at a point remote from the pivot thereof 30 and a fixed clamping bracket constructed to receive said flexible rod to hold the same in its various set positions.

7. In combination with a movable window, a curved, pivotally mounted arm, 35 means operatively connecting said arm and window at a point adjacent the topmost portion of said curve when said window is in raised position, and operating means engaging said arm at a point remote from the 40 pivot thereof.

Signed at New York in the county of New York and State of New York this 26th day of February, A. D. 1925.

EMIL KOEB.
